United States Patent Office

Des. 232,552

Patented Aug. 27, 1974

232,552

PLUMBING FITTING

Robert R. Watson, 423 Knollwood Road,
Tallmadge, Ohio 44278

Filed Dec. 13, 1972, Ser. No. 314,756

Term of patent 14 years

Int. Cl. D23—01

U.S. Cl. D23—40

FIG. 1

FIG. 3

FIG. 2

FIG. 4

FIG. 5

FIG. 1 is a perspective view of a plumbing fitting showing my new design;

FIG. 2 is a top plan view thereof;

FIG. 3 is a front elevational view thereof;

FIG. 4 is a side elevational view thereof; and

FIG. 5 is a rear elevational view thereof.

I claim:

The ornamental design for a plumbing fitting, substantially as shown.
